UNITED STATES PATENT OFFICE.

GEORGE MESTA, OF PITTSBURGH, PENNSYLVANIA.

MOTIVE MEANS FOR PICKLING AND WASHING APPARATUS.

1,107,821.

Specification of Letters Patent. Patented Aug. 18, 1914.

Application filed September 11, 1893. Serial No. 789,401.

To all whom it may concern:

Be it known that I, GEORGE MESTA, a citizen of the United States, residing at Pittsburgh, in the county of Allegheny and State of Pennsylvania, have invented a new and useful Improvement in Motive Means for Pickling and Washing Apparatus, of which the following is a full, clear, and exact description, reference being had to the accompanying drawings, forming part of this specification, in which—

Figure 1 is a vertical section of a pickling and washing apparatus embodying my invention. Fig. 2 is a cross section through the lower cylinder on the line II—II of Fig. 1.

My invention relates to pickling and washing apparatus of the general character described and claimed in Patents Nos. 20 484,664, October 18, 1892; 602,686, April 19, 1898; and 935,619, September 23, 1909, and is more particularly an improvement upon certain features of the apparatus claimed in said patent No. 935,619.

25 The object of the present invention is to improve the arrangement of the base of the machine, whereby the use of securing bolts is obviated. It has been ascertained that these securing or foundation bolts soon be come eaten out by acid and can not be relied upon.

A second object of my invention is to protect the lower end of the piston rod from injury by dirt or from the acid used in the 25 pickling process.

A third object of my invention is to provide, in connection with such protecting device, means of simple and efficient character for balancing a portion of the dead weight 40 of the moving mechanism of the machine, and thereby effect a saving in motive power.

Other objects of the invention will hereinafter appear.

In the accompanying drawings, the numeral 2 designates the vertical single-acting cylinder of the machine having therein the piston 3, secured to the piston rod 4. 5 is a spider secured to the upper end of the piston rod and provided with any desired number of arms in which are suspended the usual crates 6. 7 designates the pickling and washing vats from which the crates are actuated. These parts are, in general, the same as in my previous patents above referred to.

In accordance with my present invention,

the base 8 which carries the bearing for the downward extension of the piston rod 4 is extended downwardly to form a cylinder 9. This cylinder is seated in a hole formed to 60 receive it in the solid foundation 10, which may be of concrete. The flange portion 11 of the base member rests upon the foundation, an acid-proof backing 12 being preferably provided therefor.

13 is a bushing seated in the upper end of the cylinder, and 14 is a suitable packing above said bushing. 15 is a similar packing seated in the lower head of the main cylinder 2, which cylinder is shown as being sup-

ported by a suitable base 16, resting on the base member. Said base member is also shown as having a plurality of radially arranged strengthening ribs 17, which extend downwardly around the cylinder 9 and which are embedded in the foundation.

Two of these ribs are provided with a pipe or conduit 18, opening into the bottom of the cylinder and providing means, respectively, for the introduction of air, steam or other 75 fluid pressure and for the going out of excess pressure, water of condensation, etc. This cylinder is designed to be filled with steam, air or other elastic fluid through one of these pipes sufficient to balance a considerable portion of the dead weight of the moving mechanism of the machine, thus

very considerably reducing the quantity of the steam required in the main cylinder for the operation of the machine. This pipe 80 may be provided with any suitable pressure valve 19. The other pipe is preferably provided with a relief valve 20, which can be set to open at any desired pressure and which forms means for the escape of excess 85 pressure, as well as of water of condensation, etc.

It should be noted that in my invention the balancing of dead weight is not accomplished by gravity action, but by the pressure of an elastic fluid. This feature is essential for the success of the balancing, because a very quick descent of the pickling plunger, crates and pickled material is essential for proper pickling. If counter 100 weights or a water column were used for counterbalancing, the moving mass would be considerably increased. Since downward acceleration is the quotient of unbalanced force and total moved mass, such downward 105 acceleration would be reduced too much, if the counterbalancing were attempted by a

force which adds considerable mass. Steam or air pressure in the bottom chamber furnishes the desired force with practically no addition of mass.

5. The base member with its cylinder can be securely bedded within the foundation without the use of foundation bolts which are soon eaten off by acid. The cylinder 9 also forms a complete protection for the lower 10 end of the piston rod 4. It will also be noted that in the arrangement shown, the lower bearing for the piston rod is partially within the foundation, so that lateral strains and thrusts are transmitted directly 15 to the foundation, thus largely preventing vibration of the apparatus. The foundation also acts as an efficient protector against the action of acid on the bearing member.

It will be obvious that various changes 20 can be made in the details of construction and arrangement of the parts, without departing from the spirit and scope of my invention as defined in the appended claims. Thus, the balancing cylinder instead of being located in the base may be arranged in 25 various different ways, and many other changes may be made.

I claim:

1. In apparatus of the character described, the combination with a main cylinder, a piston rod working therethrough, and a base forming a support for the cylinder, 30 said base having an elongated bearing for the piston rod below the main cylinder, a supplemental cylinder into which the piston rod extends below said bearing, and means 35 whereby an elastic compressible fluid under pressure may be supplied to said supplemental cylinder, substantially as described.

40 2. In apparatus of the character described, the combination of a main cylinder, a piston rod working therethrough, a base member having an elongated bearing for the piston rod below the main cylinder, a supplemental 45 cylinder forming a part of said base member and into which the piston rod extends below said bearing, and means whereby an elastic compressible fluid under pressure may be introduced into the supplemental cylinder, 50 substantially as described.

3. In apparatus of the character described, the combination with a vertical main cylinder having a piston therein, a piston rod working through said cylinder 55 and formed with a downward extension, a foundation, and a base member embedded

in the foundation and having a bearing for the lower extension of the piston rod, said base member also having a closed cylinder into which the piston rod extends, substantially as described.

4. In apparatus of the character described, the combination with a main cylinder, a piston therein, a piston rod working through said cylinder and having a downward extension, a foundation, a base member seated in said foundation and having strengthening ribs, said base member carrying a bearing for the lower extension of the piston rod and also a cylinder within which 65 said extension is inclosed, and a conduit extending through one of the strengthening ribs and communicating with the lower portion of the last named cylinder, substantially as described.

75 5. In apparatus of the character described, the combination with a main cylinder, a piston therein, a piston rod working through said cylinder and having a downward extension, a foundation, a base member seated in said foundation and having strengthening ribs, said base member carrying a bearing for the lower extension of the piston rod and also a cylinder within which 80 said extension is inclosed, and conduits extending through two of said ribs, one of said conduits having a relief valve, substantially as described.

85 6. In apparatus of the character described, a vertical cylinder, a piston rod working therethrough, a load-supporting member carried by said rod and its piston, and means for utilizing an elastic compressible fluid to balance a portion of the load on the piston; substantially as described.

90 7. In apparatus of the character described, a vertical actuating cylinder, a piston working therein, a member adapted to support a variable load carried by the piston, an auxiliary balancing cylinder arranged to act upon a member connected with the piston, and means for supplying said cylinder with an elastic compressible fluid; substantially as described.

100 105 In testimony whereof, I have hereunto set my hand.

GEO. MESTA.
